WALL SEAT

Harvey G. Smith, Dallas, Tex.

Application September 6, 1951, Serial No. 245,273

5 Claims. (Cl. 155—83)

1

This invention relates to new and useful improvements in wall seats.

One object of the invention is to provide an improved folding seat in the form of a cabinet adapted to be installed in or on a wall and especially designed for use as a telephone seat.

A particular object of the invention is to provide an improved seat which, while readily foldable, utilizes only three main elements, one of which serves as a door as well as a support or leg.

A further object of the invention is to provide an improved folding wall seat of the character described, wherein the leg, which supports the seat member and forms the door or closure for the cabinet, is arranged when folded into its closed position to frictionally engage the bottom of the cabinet and hold itself in its closed position.

Another object of the invention is to provide an improved folding wall seat which by a unique mounting becomes self-fastening when folded into a closed position and is not easily unintentionally displaced from its closed position.

An important object of the invention is to provide an improved folding wall seat wherein, when folded, the entire weight of the seat and leg members is sustained by the leg member so as to hold the bottom of said leg member in firm engagement with the bottom of the cabinet and prevent unintentional unfolding of the seat.

A still further object of the invention is to provide an improved folding wall seat which is free of springs, fastenings and other hardware.

A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is a perspective view of a wall seat constructed in accordance with the invention and shown in its closed position.

Fig. 2 is a side view, partly in elevation and partly in section, of the seat in its unfolded or useable position and mounted in a wall.

Fig. 3 is a vertical, sectional view of the folded seat.

Fig. 4 is an enlarged, sectional detailed view, showing the mounting of the seat member and frictional engagement of the leg member, and

Fig. 5 is a perspective view of a seat in its unfolded or useable position and having a modified cabinet.

2

In the drawing, the numeral 10 designates a comparatively shallow cabinet comprising a vertical back wall 11, side walls 12, a top wall 13 and a bottom wall 14. The front or outer edges 5 of the side, top and bottom walls are secured to the inner face and flush with the inner edges of a rectangular face frame 15 so as to overlie a wall 16 in which the cabinet is mounted. In installing the cabinet, an opening 17 is provided in the wall 16 and said cabinet is secured therein with the frame disposed against the outer surface of said wall.

A flat leg or support member 18, in the form of a single sheet or board, is hinged to a flat seat member 19. The leg member is of such size and shape, being rectangular, as to closely fit in the opening in the front of the cabinet 10 with its outer face lying substantially flush with the outer surface of the frame 15. When in its closed position, the leg member serves as a door with its bottom edge resting firmly on the bottom 14 of the cabinet. In actual practice, good results have been had by providing merely moving clearances along each vertical side of the leg member and a slightly greater spacing between the top of the cabinet and the upper edge of said member. Thus, the leg member is of slightly less length than the opening of the cabinet.

The under or outer side of the seat member 19 has a transverse hinge bar 20 secured thereto and spaced from the top or outer edge of said member a distance substantially equal to the thickness of the leg member 18, whereby when the seat is unfolded outwardly for use, the outer edge of said seat member will be substantially flush with the outer face of the leg member 18. A transverse hinge 21, similar to a piano hinge, connects the inner side of the leg member with the underside of the bar 20.

A unique feature resides in the pivotal or hinge mounting of the inner end of the seat member 19 in the cabinet. A transverse dowel or rod 22 is secured across the outer or under side of the lower or inner end of the seat member by screws 23, and is longer than the width of said member so as to extend into openings or sockets 24 in the adjacent faces of the side walls 12. The sockets 24 are slightly vertically elongated so as to permit limited vertical movement of the ends of the dowel 22.

A handle 25 may be provided on the face of the leg member 18 to facilitate lifting of said member for unfolding the seat. A stop 26 may be mounted on the back wall 11 for holding the folded leg member in a vertical position with its outer surface flush with the frame 15.

When the seat is folded up into the cabinet, the elongated sockets permit sufficient downward movement of the seat member 19 to allow the lower edge of the leg 18, which is slightly longer than the seat member, to rest firmly on the bottom 14 of the cabinet. It is particularly pointed out that the lower edge of the folded seat member is spaced above the bottom of the cabinet and the dowel 22 is spaced above the bottom of the sockets 24. Thus, the entire weight of the seat and leg members is carried by the leg member which is thereby more firmly held in contact with the bottom of the cabinet and which transmits said weight to said cabinet bottom. In this way the leg member not only becomes a door, but the frictional engagement of its lower edge is sufficient to hold said member in the cabinet and it must be intentionally moved outwardly to displace it.

In some instances, it may not be suitable or possible to install the cabinet in a wall and in Fig. 5 a modified cabinet 26 is shown for fastening flat against a wall. The cabinet 26 includes a rectangular frame 27, having beveled outer edges 28 and an open back, which is of sufficient depth to house the folded seat. The structure of the seat is the same as that heretofore described.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A wall seat including, a cabinet adapted to be attached to a wall and having side and bottom walls and an open front, a folding seat including a support member adapted to rest upon a floor when moved outwardly and a seat member hinged to the top of the support member and having its inner end in the cabinet, said cabinet having vertically elongated openings in its side walls, and an element secured to the seat member having its ends confined in the side wall openings, whereby the bottom edge of the support member may frictionally engage the bottom wall of the cabinet when the seat is folded into said cabinet and restrain the seat against outward movements, the support member forming a closure for the cabinet.

2. A wall seat including, a cabinet adapted to be attached to a wall and having an open front,

and a folding seat adapted to be folded into the cabinet through the open front thereof and including a seat member hinged to a leg member, the leg member closing the open front of the cabinet and resting on the bottom thereof when the seat is folded, the seat member being loosely hinged in the cabinet to permit the leg member to rest on the bottom of the cabinet.

3. A wall seat including, a cabinet adapted to be attached to a wall and having an open front, and a folding seat adapted to be folded into the cabinet through the open front thereof and including a seat member hinged to a leg member, the leg member closing the open front of the cabinet and forming a door therefor, the inner end of the seat member being spaced from the bottom of the cabinet and having pivots movable vertically in the sides of the cabinet, whereby the leg member supports the weight of the seat member when folded into the cabinet and whereby said seat member may move upwardly and downwardly in the cabinet to permit the bottom edge of the leg member to rest upon the bottom of the cabinet.

4. A wall seat including, a cabinet adapted to be attached to a wall and having an open front, and a folding seat adapted to be folded into the cabinet through the open front thereof and including a seat member hinged to a leg member, the leg member closing the open front of the cabinet and forming a door therefor when the seat is folded into the cabinet, the lower end of the seat member being spaced from the bottom of the cabinet and having loose pivots in the side walls of the cabinet, whereby the weight of the seat member is carried by the leg member and the leg member rests upon and transmits said weight to the bottom of the cabinet when closed.

5. A wall seat as set forth in claim 1, wherein the cabinet includes an open frame adapted to be fastened to the outer surface of the wall.
